(57) **CLAIM**

The ornamental design for combined display device and screen with an animated icon, as shown and described.

DESCRIPTION

FIG. 1 is a front view of the combined display device and screen with an animated icon;

FIG. 2 is a front view of the second image thereof;

FIG. 3 is a front view of the third image thereof;

FIG. 4 is an enlarged view of the portion A in FIG. 1, the combined display device and screen with animated icon is shown partially for clarity of illustration;

FIG. 5 is an enlarged view of the portion A in FIG. 2, the combined display device and screen with animated icon is shown partially for clarity of illustration; and,

FIG. 6 is an enlarged view of the portion A in FIG. 3, the combined display device and screen with animated icon is shown partially for clarity of illustration.

The outermost broken lines show the display device and forms no part of the claimed design. The dot-dash broken line indicates the portion A in FIGS. 1-3 and forms no part of the claimed design. The remaining broken lines forms no part of the claimed design. The appearance of the image transitions sequentially between the images shown in FIGS. 1-3. The process or period in which an image transitions to another forms no part of the claimed design.
